UNITED STATES PATENT OFFICE

JOHN S. PAYNE, OF MIDLAND PARK BOROUGH, NEW JERSEY

DRIVING MECHANISM FOR SNOWPLOWS

Application filed October 23, 1926. Serial No. 143,535.

My invention relates to an improved construction of bearing block and bed for the stub shafts of snow plow engines, and has for an object, to provide a construction which will enable the stub shafts, with the bevel gears mounted thereon, to be assembled in the machine, and disassembled therefrom, without disassembling other parts of the machine, whereby a material economy of time and labor will be effected.

It has been the practice, in snow plows heretofore known, to drive the rotor by a main shaft, carrying a bevel gear, which is driven by two smaller bevel gears, mounted on stub shafts, disposed at a right angle to the main shaft, one on each side thereof. The stub shafts are journalled in bearing supports, formed integrally with the bed plate casting, which type of construction has necessitated the removal, vertically, of all three shafts, with their gears, and the disconnection of many associated parts, such as both connecting rods, and both eccentric rods, whenever it has been necessary to repair or replace one of the small gears. This disadvantage is attended with the further disadvantage of having to dismantle substantially all of the housing at the front end of the snow plow, to permit removal of the three shafts. As the small gears are subjected to a great amount of wear, their frequent repair and renewal are incidents of service, and the operations of assembling and disassembling the gears, involves great inconvenience and expense.

In my improved construction, the bearing blocks for the stub shafts are formed with dove tails, which fit in complementary grooves in the bed, thus permitting the bearing blocks, stub shafts, and small bevel gears to be moved, as a unit, horizontally away from the machine without disassembling any of the other parts of the machine, the unit being of a size to permit it to be moved out of the usual door in the side wall of the housing.

The improvement claimed is hereinafter fully set forth.

In accompanying drawing: Figure 1 is a half vertical transverse section, of the rotor

driving mechanism of a snow plow embodying my invention, showing one of the stub shafts with its bed plate, bearing block, crank, and bevel gear; and, Fig. 2, an end view of the construction shown in Fig. 1, the crank being removed.

In the practice of my invention, referring descriptively to the specific embodiment thereof which is herein exemplified as applied to a snow plow, the main shaft, 10, for driving the rotor, of usual construction, (not shown), extends longitudinally of the plow frame, and carries a large bevel gear, 11, which is driven by two smaller bevel gears, 12, mounted on stub shafts, 13, disposed one on each side of the main shaft, and at a right angle thereto. Each stub shaft carries a crank, 14, and is mounted in a bearing block, comprising a body, 15, formed with a dovetail base, 15^a, and a cap, 16, detachably connected to the body by bolts, 17. A flange, 18, extends from each side of the body, and is adapted to receive bolts, 19, which detachably fasten the block to the bed, 20, connected to the middle sills, 21, of the snow plow frame.

The bed, 20, is formed with a dovetail groove, 20^a, adapted to receive the dove tail, 15^a, on the body of the bearing block, and is provided with bolt holes which receive the bolts, 19, for securing the blocks in place. The grooves, 20^a, are of sufficient width to permit the small gears, when assembled on their stub shafts, to be moved therethrough.

In assembling the machine, a bearing block, stub shaft, small bevel gear, and crank, are assembled as a unit, which is moved into place, to bring the small bevel gear into mesh with the large bevel gear, 11, by sliding the dovetail, 15^a, of the block, into the groove, 20^a, of the bed. Suitable keys, 22, are then driven in between the sides of the groove, and the sides of the dove tail, 15^a, to properly align the shaft, after which the bolts, 19, are applied to anchor the bearing block to the bed.

It is within the contemplation of the invention to drill the holes for the bolts, 19, in the bed, after the stub shafts have been aligned, to ensure the retention of the stub

shafts in proper position. It is further within the contemplation of the invention to form the bed as an integral part of the longitudinal sills of the snow plow.

From the foregoing description, it will be obvious that, when it is desired to repair or replace a small bevel gear, it is merely necessary to unfasten the bolts, 19, whereupon the stub shafts, small gear, crank, and bearing block, may be moved, as a unit, horizontally away from the remainder of the machine. The improvement obviates the disadvantage, present in snow plows heretofore known, of having to remove all three shafts with their gears, from the machine, and dismantling substantially all of the housing at the front of the plow, to enable such removal.

I claim as my invention and desire to secure by Letters Patent:

- 20 1. In a device of the character described, the combination of a journal box having lateral flanges and a downwardly extending portion therefrom providing a rigid unitary structure for the journal; a support for the box having a channel for engaging the said downwardly extending portion, and lateral extensions beneath said flanges; and means for securing the box relative to the support.
- 25 2. In a device of the character described, the combination of a journal box having lateral flanges and a downwardly extending portion therefrom providing a rigid unitary structure for the journal, said portion having a horizontal base and downwardly and outwardly flaring partial side walls; a support for the box having a channel for engaging said downwardly extending portion having a horizontal seat for supporting said horizontal base, and side walls opposite to
- 30 and spaced from the said flaring walls, and lateral extensions beneath said flanges; and means for securing the box relative to the support, comprising keys engaged in said spaces for holding the box upon its seat.
